UNITED STATES PATENT OFFICE.

LORENZ MUTHER, OF OAK PARK, ASSIGNOR TO THE UNION SPECIAL SEWING MACHINE COMPANY, OF CHICAGO, ILLINOIS.

WELT-GUIDE FOR SEWING-MACHINES.

SPECIFICATION forming part of Letters Patent No. 427,352, dated May 6, 1890.

Application filed February 25, 1889. Serial No. 301,079. (Model.)

To all whom it may concern:

Be it known that I, LORENZ MUTHER, a citizen of the United States, residing in Oak Park, in the county of Cook and State of Illinois, 5 have invented a new and useful Improvement in Machines for Sewing Welted Seams, of which the following is a specification.

In sewing welts into the seams of shoes it is desirable that the welt should be left out 10 of those portions of the seam which in the subsequent manipulation must be folded into other seams running across or at right angles to the welted seam.

The object of my invention is to produce a 15 welt-sewing machine, in the use of which the operator may at the proper time withdraw the welt from the line of sewing and from between the edges of the pieces being sewed, so that the machine may be kept in motion notwithstanding such withdrawal of the welt, 20 and the seam be proceeded with and finished precisely as though no welt had been introduced into any part of it; and in carrying out this object I make the guide for the welt movable laterally with regard to the line of the 25 seam and provide it with a lever or equivalent convenient means, whereby it may be thus moved when the sewing has reached the point where the welt should be withdrawn.

30 The invention consists in a guide for the welt and a spring-controlled plate for carrying said guide, and which is movable laterally away from the seam and is provided with a lever for its convenient operation.

35 In the accompanying drawings, which form a part of this specification, and in which similar letters of reference indicate like parts, Figure 1 is a perspective of the bed-plate of a sewing-machine with my welting attachment in place thereon. Fig. 2 is a plan view of the attachment. Fig. 3 is a section upon the line 3 3 of Fig. 2. Fig. 4 is a section upon the line 4 4 of Fig. 2, showing the two thicknesses of leather being joined, with the welt 40 in position between them ready to be sewed into the seam. Fig. 5 is a section similar to Fig. 4, showing the welt withdrawn from between the leather and the position to which it may be moved by the movable guide of my 45 invention; and Fig. 6 shows the thicknesses 50

of leather and the welt in the position they occupy at the instant of sewing them together.

In said drawings, A represents the bed-plate of the sewing-machine, a the presser-foot, and a' the aperture in the latter for the passage 55 of the needle.

B is a plate adapted to be slid under the holding-ledges of the bed-plate A in position for operation, and b is a set-screw for fastening the plate after it has been positioned. 60 Secured to this plate B is a block of metal C, in which is formed a slideway c.

D is a slide working in said slideway c and carrying at its outer end a plate E and a looped or doubled strip e, the latter being conveniently secured to the slide by the screw c'. The outer edge of the plate E acts as the tongue of the guide and the strip e acts to confine or hold the welt upon such tongue. I also mount upon said plate E another doubled 70 piece of metal F, through which the welt is passed in like manner as through the strip e. This last-mentioned strip F acts in conjunction with the rider-piece f, also mounted on the plate E, to straighten the welt in case it 75 should be twisted as it approaches the needle. The guide thus described would act in the ordinary manner if stationary; but by securing it to the side and providing the latter with a suitable operating device—such as a lever 80 G, pivoted to the block C and connected to the slide by the pin g, working in the elongated slot h of the lever—the operator is enabled, when the proper point in the seam has been reached, to quickly move the guide laterally, 85 thereby bringing the welt to the position shown at Fig. 5, and allowing the completion of the seam without stopping the machine and without severing the welt at the time or removing it from the machine. The lever or 90 other slide-operating device should have limits placed upon its motion, so that it may not carry the welt too far within the seam upon the one hand nor too far away from it upon the other, and hence I provide stops consisting 95 of a plate H at one side of the lever and a set-screw i at the other side.

I have shown the invention in the form of a removable attachment to be applied to existing machines; but it of course may be made 100

a permanent part of the machine. The spring *m* acts against the farther end of the slide to keep the guide up to its work, and also returns it to the operating position after it has been moved therefrom, and the loop-guide *F* may also be accompanied by an adjustable reversed loop *j*, the ends whereof are within the loop *F* and act as guides to the edges of the welt.

- 10 In the practical operation of the invention, where large quantities of shoes are being made, a continuous welt running through the seams of a series of shoes may be used, and only be severed subsequent to the sewing of 15 the series. My improved guide permits this to be done, as it carries the welt back into the seam as readily as it withdraws it therefrom.

I claim—

1. The welting attachment for sewing-machines, comprising a sliding spring-controlled guide-carrying plate movable laterally toward and away from the line of stitching, a guide thereon, and a lever for imparting lateral movement to said plate against the action of 25 the spring, substantially as described.
2. In combination with a suitable base-plate, a block supported thereby, a welt-guide

movable on said block, a lever pivoted to the block at one end and secured to said guide, and a spring for keeping said guide normally 30 pressed forward, substantially as described.

3. In combination with a suitable base-plate, a block supported thereby, a welt-guide movable on said block, a lever pivoted at one end to the block and secured to said guide, 35 stops secured to said block for limiting the movement of said lever, and a spring for keeping the welt-guide normally pressed forward, substantially as described.

4. In combination with the bed-plate of a 40 sewing-machine, a plate *B*, secured thereto, a metallic block attached to said plate *B*, a welt-guide movable on said block, a lever pivoted at one end to said block and provided with a longitudinal slot, a pin passing through 45 said slot into the guide, stops for limiting the movement of said lever, and a spring for keeping the guide normally pressed forward, substantially as described.

LORENZ MUTHER.
